UNITED STATES PATENT OFFICE

NORMAN H. SAUNDERS, OF CHICAGO, AND CLARENCE E. LOMAX, OF OAK PARK, ILLINOIS, ASSIGNEES, BY MESNE ASSIGNMENTS, TO ASSOCIATED ELECTRIC LABORATORIES, INC., OF CHICAGO, ILLINOIS, A CORPORATION OF DELAWARE

TELEPHONE SYSTEM

Application filed August 24, 1931. Serial No. 558,912.

This invention relates in general to telephone systems, particularly telephone systems comprising a manual central office or switching center and a number of relatively small automatic offices, and it is concerned primarily with circuits and apparatus for interconnecting the offices of such systems.

The traffic conditions and geographical location of the offices of a multi-office system of the type above-referred to occasionally make it desirable to interconnect the various offices by one or more trunk lines which extend from the switching center through all of the automatic offices. Each automatic office is provided with switching apparatus associated directly with the trunk line to enable the operator at the switching center to select anyone of the offices in which the line of a wanted subscriber is accessible.

Trunk lines of this type may be arranged for handling calls from any automatic office to the switching center in addition to the calls from the switching center to the various automatic offices. In this case it is necessary to make provisions for busying the trunk line in the various offices whenever the same is in use in a connection. It is also desirable that the trunk line be arranged for use in connecting subscribers in different ones of the automatic offices.

The system chosen to illustrate the present invention is one in which the automatic offices employ switching equipment of the general type disclosed in United States Patent No. 1,772,690, granted August 12, 1930 to N. H. Saunders. Each automatic office is designated by a particular office digit which identifies this office. Two offices have been shown in the drawings, one designated by the digit 3 and the other by the digit 5. These offices will be referred to hereinafter as office A and office B, respectively.

The provision of new and improved circuits and apparatus for use in systems of the above type is the main object of the present invention. The various features of the invention relate to improvements in control circuits, supervisory circuits, and associated switching apparatus tending to make such systems more efficient and re-

liable. These features together with the operation of the system embodying the invention will be described in detail, reference being had to the accompanying drawings comprising Figs. 1 and 2. These drawings 55 show by means of the usual circuit diagrams a sufficient amount of equipment in a multi-office system embodying the invention to permit the invention to be readily explained and understood. Fig. 1 shows the 60 apparatus associated with an interoffice trunk line at a switching center and also a part of the apparatus at an automatic office. Fig. 2 shows the trunk apparatus and exchange switching apparatus at another automatic office. In order to be best understood, the drawings should be placed with Fig. 2 to the right of Fig. 1 and with correspondingly designated lines in alignment.

Referring now to Fig. 1 the apparatus 70 TR, appearing above the broken line, is a relay group terminating the trunk line T at a manual switching center. The trunk line extends to all the offices of the system and at each office a branch connection is made to 75 the office switching apparatus. One such branch is shown between the two broken lines. This branch extends to the switching apparatus shown in Fig. 2 which is located in office A. A second branch of the trunk 80 extends to the switching apparatus SA shown below the lower broken line in Fig. 1 which is located in office B. There may be any number of other offices connected in the trunk line in the manner shown and in 85 each case the equipment provided will be substantially the same as that shown in the present drawings.

The trunk relay group TR in which the trunk line T terminates is provided with a 90 jack J by means of which the operator completes connection to and from the trunk. Connections are completed by means of a manual cord circuit C which may be of any suitable type and which is shown only in 95 skeleton form. A calling device D common to all trunks at the manual operator's position may be connected to the trunk line by means of the key K.

The switching apparatus SA shown at the 100

bottom of Fig. 1 is connected to the trunk line at the office B. Only the essential parts of the switching apparatus SA have been shown as this apparatus is exactly the same 5 as switching apparatus SA1 shown in Fig. 2, except for the wiring of the bank contacts of the rotary switch. Relays and contacts have been designated similarly to corresponding relays and contacts of the equipment shown in Fig. 2 for convenience in describing the operation of the circuits. For example, relay 21 in Fig. 1 corresponds to relay 121 in Fig. 2, etc.

Referring now to Fig. 2 the switching apparatus SA1 is associated with the trunk line T at office A. This apparatus consists of a group of relays and a rotary switch which is directly controlled over the trunk. Lineswitch LS is adapted to be associated individually with the branch of the trunk T and has access to local connectors in office A of which one, connector C, is shown in skeleton form. Lineswitch LS1 is a lineswitch similar to lineswitch LS and is individual to the subscriber's line S. This lineswitch and other similar lineswitches have access to the connectors of the automatic office. The connector has access to trunk line T and other similar trunk lines, and also to the 30 various subscribers' lines which terminate in this office. The lineswitches and connector shown in the present application are similar to those shown in the Saunders patent previously referred to.

Having briefly described the invention and the system embodying the same, the operations involved in establishing various connections in the system will now be described in detail. The establishment of a connection 40 from the manual switching center to the subscriber's station S in office A will be considered first.

Assuming that a call from a distance point is received by the operator at the switching center, the operator will answer this call by means of a cord circuit, such as cord circuit C, and on determining that the call is for the subscriber S, will insert the calling plug P of the cord circuit into the jack J of an 50 idle trunk line. Upon the insertion of the plug into the jack a circuit will be closed for relay 9 by way of the sleeve of the jack plug and that relay will operate. Relay 9 in operating completes the circuit at contacts 55 18 for supervisory lamp L1, disconnects relay 8 from the trunk line at contacts 16, and connects relay 7 to the trunk line at contacts 17. A circuit may now be traced from ground, winding of relay 7, contacts 60 11 and 17, left-hand windings of repeating coil R, trunk conductors 1 and 2 in parallel, branch conductors 3 and 4 in parallel, contacts 134 and 139, contacts 140 and 145, windings of impedance I, contacts 148 and 159, 65 relay 129 to battery. A parallel circuit may

be traced for relay 7 including branch conductors 5 and 6 in parallel, contacts 34 and 39, contacts 40 and 45, impedance I', relay 29 and battery. Other similar parallel circuits will exist in all other offices which are connected to the trunk line T. Relay 7, and relay 129 and the corresponding impulse relays in the other offices will operate over the above circuits. Relay 7 opens a point in the circuit of supervisory lamp L1 at contacts 13. Relay 129 completes a circuit for relay 130 at contacts 163 and similar circuits are completed by the corresponding relays in the other offices. Relay 130 on operating applies ground by way of contacts 165 and 146 to conductor 173 to mark the trunk line busy to the connectors in office A. A point in the release circuit is opened at contacts 166, the impulsing circuit for the rotary switch is prepared at contacts 167, and a point in the switching circuit is prepared at contacts 168.

After having established connection with the trunk line the operator at the switching center will actuate key K thereby disconnecting relay 7 from the trunk line at contacts 11 and substituting therefor ground through impulse contacts 10 of the calling device by the operation of contacts 12. Relay 7 will restore and complete the circuit of lamp L1, but the impulse relays corresponding to relay 129 at various offices will now be operated over the circuit extending to ground through the impulse contacts of the dial.

As previously stated the office A is designated by the digit 3, office B is designated by the digit 5. Other offices will have designations which distinguish from the two mentioned, but in every case the operation will be in general the same and need not be described in detail. The calling operator will accordingly dial the digit 3, thereby interrupting the previously traced circuit of the impulse relays three times. The impulse relay in each office will respond to the impulses and operate the associated rotary switch as will be described for relay 129 of switching apparatus SA1. Relay 129 upon restoring for each impulse completes a circuit by way of contacts 162 and 167, winding of relay 131, rotary magnet 132 to battery. Relay 131 and the magnet operate, the latter advancing wiper 178 of the rotary switch one step. Relay 131 is slow-to-release and remains operated throughout the series of impulses. Relay 130 is also slow-to-release and remains operated when its circuit is momentarily opened during impulsing at contacts 163. The rotary magnet thus advances the wiper 178 step-by-step until the third contact, that is, contact 170 is reached. Shortly after the last impulse of the series relay 131 will release, thereby closing a circuit by way of contacts 168, 169, wiper 178, contact 170, lower winding of relay 121 to battery. The

release of the relays corresponding to relay 131 in the other offices will complete circuits which are different than the one just described, since the other offices are designated by digits other than 3 and the rotary switch banks are accordingly wired in a different manner. More specifically, in the other offices circuits will be closed for the relays corresponding to relay 126 and this relay will operate to disconnect the normally connected impulse relay from the trunk line as will be explained subsequently.

Referring now to the operation of switching apparatus SA1 upon the completion of the dialling of the office digit, relay 121 will operate over the circuit previously traced and at contacts 135 and 138 will extend the trunk conductors through to lineswitch LS. It will be recalled that ground through the impulse contacts of the calling device is connected to the two trunk conductors, and this ground extending by way of contacts 103 and 104, relay 101 to battery operates relay 101. A circuit is thereby closed at contacts 109 for the pull-down winding of lineswitch LS. The plunger of the lineswitch is accordingly forced into the banks closing contacts 179-182 which extends the connection through to connector C. The impulse and release relays of the connector operate in the usual way and return a holding ground over release trunk conductor 106. This ground energizes the holding winding of the magnet 102 of the lineswitch LS and prevents the release of the lineswitch upon the release of relay 101 which is brought about by the opening of contacts 103 and 104 upon the operation of the plunger. Holding ground extends back by way of conductor 176, contacts 142 and 137, through the upper winding of relay 121 and maintains this relay in operated condition. The trunk conductors have been disconnected from impulse relay 129 at contacts 134 and 139 by the switching operations just described and relay 129 releases. The circuit of relay 130 is opened at contacts 163 and relay 130 restores and completes a circuit for release magnet 133 at contacts 166. The release circuit includes off-normal contacts 118 which closed upon the first step of the rotary switch. The rotary switch is accordingly restored to normal by the operation of the release magnet and upon reaching normal condition, off-normal contacts 118 are again opened and the release magnet accordingly restores.

The calling operator now dials the number of the called subscriber in the called office. Connector C is stepped to the contacts of the called line in a well known manner, as is described in detail in the Saunders patent previously referred to. After dialling the last digit the operator will restore key K to normal again connecting relay 7

to the trunk line. The called subscriber will be signalled automatically in the usual manner and relay 7 will be operated in series with the impulse relay of the connector during this interval. When the called subscriber answers, the resistance of the operating circuit is increased and relay 107 restores, thereby completing a circuit for supervisory lamp L1, which glows to give answering supervision. When the called subscriber hangs up at the end of the conversation, relay 107 will again operate and open the circuit for lamp L1 which will be extinguished to indicate to the operator that the connection is to be taken down. The operator will accordingly withdraw the plug from the jack, thereby releasing relay 109 which disconnects relay 107 from the trunk. The circuit of the impulse relay of the connector is accordingly opened and that relay releases and the connector restores to normal in the usual manner.

The apparatus involved in other offices than the one called upon the dialling of the first or office designating digit will now be described. In this case it will be assumed that a subscriber at office B is called in which case the office digit 5 will be dialled by the operator. The rotary switches in the various offices will be set on the fifth contact of their respective banks in the manner previously described for calls to office A. Relay 21 of the switching apparatus SA in office B will operate and extend the connection through to the associated lineswitch which will operate as described for lineswitch LS. Referring now to Fig. 2 upon the release of relay 131 following the last impulse of the series, a circuit will be completed by way of contacts 168 and 169, wiper 178, bank contact 171, contacts 153, winding of relay 126 to battery. Relay 126 is provided with a single armature spring to the end of which a weight is affixed. The relay on being energized immediately closes contacts 154, thereby completing an operating circuit for relay 127. Upon the release of relay 126, however, the armature spring will vibrate due to the weight, and will intermittently close contacts 154 and 155 until amplitude of vibration decreases to a predetermined extent. When this point is reached, relay 127 will restore to normal. The operation of relay 127 completes a circuit at contacts 156 for relay 125. Relay 125 operates and completes a circuit for relay 123 at contacts 151, completes a circuit for relay 122 at contacts 152, and at contacts 153 opens the circuit for relay 126. Relay 123 operates and connects busying ground to conductor 173 at contacts 147, disconnects line relay 129 from the trunk at contacts 148, and at contacts 149 connects high resistance relay 104 to the trunk line. Relay 124 may operate momentarily at this time

although this is of no consequence. Relay 122, whose circuit was closed by the operation of relay 125, is slow-to-operate and, after an interval, operates and disconnects the trunk conductors from relay 124 at contacts 140 and 145. Relay 126 deenergizes upon the opening of its circuit at contacts 153 and the armature vibrates as previously explained. Holding relay 127 remains operated for a predetermined interval which is determined by the adjustment of the weighted spring. An interval of fifteen seconds is ordinarily sufficient in the case where three additional digits must be dialled to complete the connection, and it will be assumed in the present case that the relay 127 remains operated for this interval after the opening of the circuit of relay 126. It will be seen from the foregoing that the trunk conductors will be entirely clear at all offices other than the particular one called during this fifteen second interval. This arrangement increases the operating efficiency of the trunk and permits the use of standard connectors and other apparatus in the various offices. Inasmuch as the impulse relay of the connector is the only relay connected to the trunk during this period the operation will be as reliable as if only one office were served by the trunk. At the end of the cut-off interval, relay 127 will restore and open the circuit of relay 125. Relay 125 will accordingly restore and open the circuit of relays 123 and 122. Relay 123 is slow-to-release and remains operated for a short interval after its circuit is opened, whereas relay 122 will restore almost immediately. The talking conductors will accordingly be extended by way of contacts 140 and 145, impedance I, contacts 149, relay 124 to battery. Relay 124 will operate in parallel with the similar relays in other exchanges and with the impulse relay of the connector in the called office. Relay 124 will close the circuit for relay 123 before it has had time to deenergize and relay 124 will remain operated and maintain the equipment in the position just described. Impulse relay 129 in the meantime will have released followed by release of relay 130 and the restoration of the rotary switch to normal.

Upon the release of the connection the switching apparatus SA in the called office will restore in the manner previously described for calls to office A. The high resistance supervisory relays at the various offices (relay 124) will also restore. These relays will in turn permit the restoration of the relays corresponding to relay 123, thereby returning all equipment to normal condition.

In the case of a call originating in one of the automatic offices, for example at the substation S, for a subscriber in another office, the operation will be as follows. The sub-

scriber on initiating a call operates line-switch LS1 which immediately connects with an idle connector, such as C. Connector C is operated in the usual way to the level in which the trunk lines are accessible and an idle trunk line is accordingly selected. Assuming this selected trunk line to be the trunk line T, a circuit will be completed over the test wiper of the connector, conductor 173, contacts 146, 164, 142, and 136, relay 128 to battery. Relay 128 on operating connects ground to conductors 172 and 174 at contacts 158 and 161, and at contacts 157 connects ground to trunk conductor 3. A circuit is closed for relay 122 at contacts 160 and the latter relay operates and locks to ground at contacts 143. The circuit of relay 128 is accordingly opened at contacts 142 and this relay releases a short time after the opening of the circuit. The momentary connection of ground to the conductors 172 and 174 effects the operation of ring-cut-off relay in the connector in the well known manner, and the operation of relay 122 extends the trunk conductors through to conductors 119 and 120 at contacts 141 and 144. A talking connection is thus prepared between the calling subscriber and the operator at the switching center.

Referring now to the apparatus at the switching center, the momentary connection of ground to conductor 3 causes the operation of relay 8 of the trunk relay group TR. This relay closes a circuit for the line lamp L at contacts 14 and at contacts 15 connects ground to the two trunk conductors in parallel. Relay 8 is accordingly held up over the circuit including contacts 15 and 16 after the release of relay 128 of the trunk apparatus SA1. The line lamp glows to indicate the arrival of the call to the operator. In offices other than the one in which the call originated the impulse relays are operated by the connection of ground to the trunk conductors and these relays accordingly operate and mark the trunk busy in the banks of a connector at the respective offices as described in previous connections. The operator on answering the call by inserting the plug P of the cord circuit C into jack J operates relay 9 which in an obvious manner substitutes relay 7 for relay 8 in the connection to the trunk. Relay 7 operates in series with the impulse relays of the switching units at the various offices and opens the circuit of the supervisory lamp. Relay 8 restores and opens the circuit of the line lamp L and also disconnects the ground from the trunk at contacts 15.

In case the call is for a subscriber in a different system the operator will accordingly extend the connection by inserting the calling plug of the cord circuit into a trunk extending to the wanted exchange or system. If, however, the call is for a subscriber in

one of the offices served by the trunk line T, such for example as the office B, the operator will actuate key K and thereby substitute the calling device D for relay 7. The wanted subscriber will be called in exactly the same manner as previously described for calls originating at the switching center, although in this case since the impulse relay at the calling office A is disconnected from the line there will be no operation of the switching apparatus at that office. The connector at the called office will be operated to extend the connection to the called line and the disconnect apparatus at the other offices will function as previously described to connect the high resistance supervisory relays to the trunk.

At the termination of the connection, the called subscriber on hanging up first will give the operator disconnect supervision in the same manner as for calls originating in the switching center. If the calling subscriber hangs up first, the calling connector will restore and open the previously traced holding circuit for relay 122 which will also restore. Relay 122 will reconnect impulse relay 129 to the trunk conductors, thereby permitting relay 7 of the trunk relay group TR to operate and give the calling operator the usual disconnect supervision. The release of the connection in this case will be brought about by the withdrawal of the plug from the jack in the usual manner.

What is claimed is:

1. In a telephone system, a switching center and a plurality of automatic offices serially connected by a trunk line, subscribers' lines terminating in said offices, means at the switching center for transmitting digit impulses representing the number of a called subscriber's line over the trunk line, the first digit of the number designating the office in which the called line is located, a switching device in each office operated responsive to the transmission of the first digit of the called number, and means controlled by the devices in the offices other than the one designated by the digit transmitted for temporarily clearing the trunk line of all connections in such offices.

2. In a telephone system, a switching center and a plurality of automatic offices serially connected by a trunk line, switching devices in said office connected to the trunk line in multiple, subscribers' lines terminating in said offices, means at the switching center for transmitting digit impulses corresponding to the number of a called line over the trunk line, means for operating all of said switching devices responsive to the first digit of the called number, and means operated under control of said devices for temporarily disconnecting the devices from the trunk line.

3. In a telephone system, a switching cen-

ter and a plurality of automatic offices serially connected by a trunk line, subscribers' lines terminating in said offices, means at the switching center for transmitting digit impulses corresponding to the number of a called line over the trunk line, the first digit of the number designating the office in which the called line is located, a switching device in each office operated responsive to the first digit of the called number, switching apparatus in each office for extending connections to called lines, means controlled by the switching device in the office designated by the digit called for rendering the switching apparatus at that office directly operable by the remaining digits of the called number, and means controlled by the devices in the other offices for clearing the trunk line of all connections for an interval long enough to permit the transmission of said remaining digits.

4. In a telephone system, a plurality of offices, a trunk line connecting said offices, switching devices connected to the trunk line at each office, means for transmitting a series of impulses designating one of said offices over the trunk line to operate said devices simultaneously, and means associated with each device and controlled responsive to the operation thereof for disconnecting the devices from the trunk line.

5. In a telephone system, a plurality of offices connected by a trunk line, a switching device in each office connected to the trunk line, means for transmitting a series of impulses designating one of said offices over the trunk line to operate said devices simultaneously, and means associated with each device and controlled responsive to the operation thereof for temporarily disconnecting the devices from the trunk line in all offices except the one designated by said impulse series and for connecting a different switching device to the trunk line in the office designated by said impulse series.

6. In a telephone system, a manual office, a plurality of automatic offices, a trunk line extending from the manual office to all of said automatic offices, switching apparatus in each automatic office connected to the trunk line, other switching apparatus in each office for extending connections to called lines, means at the manual office for transmitting a series of impulses designating one of said automatic offices over the trunk line to operate the switching apparatus in each automatic office, and means responsive to the operation of said apparatus for temporarily disconnecting the same from the trunk line and for rendering the other switching apparatus in said one office directly controllable over the trunk line.

7. In a telephone system, a manual office, a plurality of automatic offices, a trunk line extending from the manual office through

70

75

80

85

90

95

100

105

all of said automatic offices, switching apparatus in each automatic office connected to the trunk line, means at the manual office for transmitting a series of impulses designating one of said automatic offices over the trunk line to operate the switching apparatus in each office, and means responsive to the operation of said apparatus for clearing the trunk line of all connections in all offices except the one designated.

8. In a telephone system, two offices, a trunk line extending to said offices from a remote control point, means at the control point for transmitting an office selecting digit over the trunk line to operate switching apparatus in both of said offices simultaneously, means at the control point for transmitting line selecting digits over the trunk line to operate other switching apparatus in the selected office, and means controlled by the apparatus in the non-selected office for clearing the trunk line of attachments during the transmission of the office selecting digits to prevent interference with the operation of the apparatus in the selected office.

9. In a telephone system, two offices, a trunk line extending from a remote control point to said offices, means at the control point for transmitting an office selecting digit and line selecting digits over the trunk line, switching apparatus at each office operated responsive to the office selecting digit, other switching apparatus in the selected office operated responsive to the line selecting digits, and disconnect apparatus at the non-selected apparatus controlled by the switching apparatus for clearing the trunk line of attachments in that office for a predetermined time to prevent interference with the operation of the apparatus in the selected office.

10. In a telephone system, a trunk line, a plurality of impulse relays connected to the trunk line, a switching device controlled by each relay, means for simultaneously operating said relays to set the respective devices, and means associated with each device and operated responsive to the setting of the device for disconnecting the associated impulse relay from the trunk line.

11. In a telephone system, a trunk line, a plurality of relays connected to the trunk line at different points, a plurality of other relays, a switching device for each of said first relays, means for simultaneously operating said first relays over the trunk line to set the respective devices, and means associated with said devices and operated responsive to the setting thereof for disconnecting said first relays from the trunk line and for connecting said other relays to the trunk line at said different points.

12. In a telephone system, a trunk line, a plurality of relays normally connected to

the trunk line at different points, a plurality of other relays, a switching device for each of said first relays, means for simultaneously operating said first relays over the trunk line to set the respective devices, and means responsive to the setting of said devices for disconnecting said first relays from the trunk line and for connecting said other relays to the trunk line after a predetermined interval of time.

13. In a telephone system, a trunk line, a plurality of switching devices connected to the trunk line, a non-numerical switch associated with each of said devices, means for simultaneously setting said devices to corresponding positions, and means controlled by the setting of the devices for disconnecting all of the devices from the trunk line and for connecting the switch associated with a particular one of said devices to the trunk line.

14. In a telephone system, a two-conductor trunk line, a plurality of relays connected to the trunk line, a switching device associated with each relay, means for simultaneously operating said relays over the two conductors of the trunk line in parallel to set the respective switching devices, and means responsive to the setting of said devices for temporarily disconnecting said relays from the trunk line.

15. In a telephone system, a trunk line extending from one office to a plurality of other offices, a line relay and a cut-off relay associated with the trunk line in each of said other offices, means for seizing the trunk line at any of said offices to extend a connection, means responsive to the seizure of the trunk line at said one office for operating the line relays at all of said other offices, and means responsive to the seizure of the trunk line at one of said other offices for operating the cut-off relay at that office and for operating the line relays at the remaining ones of said other offices.

16. In a telephone system, a trunk line extending from one office to a plurality of other offices, a signal for the trunk line at the first office, a relay connected to the trunk line in each of the other offices, means controlled by said relays for marking the trunk line busy in the respective offices, means responsive to the seizure of the trunk line at the first office for operating all of said relays, and means responsive to the seizure of the trunk line at one of said other offices for operating said signal and the relays at all of the other offices except the one at which the trunk line is seized.

17. In a telephone system, a trunk line extending from one office to a plurality of other offices, a relay connected to the trunk line at each office, means controlled by said relays for marking the trunk line busy in the respective offices, means responsive to the seizure of the trunk line at the first office

for operating the relays at all of said other offices, means responsive to the seizure of the trunk line at one of said other offices for operating the relays at the remaining offices, 5 and means responsive to the operation of the relay at the first office for maintaining the other operated relays in operated condition independent of control from the office in which the trunk line was seized.

10 18. In a telephone system, a manual office and a plurality of automatic offices serially connected by a trunk line, a calling line in one automatic office, a called line in another automatic office, an automatic switch at said 15 one automatic office directly controlled over the calling line for establishing a connection with the manual office over the trunk line, and an automatic switch at said other automatic office directly controlled from 20 the manual office over said trunk line for extending the connection to said called line.

19. In a telephone system, an operator's switchboard, a plurality of automatic office, a trunk line extending from the switchboard 25 to all of said offices, switching apparatus at each office connected to the trunk line, a called line in one of said offices, a called line in another of said offices, means at said one office for establishing a connection between the calling line and the switchboard via 30 the trunk line, means including the switching apparatus at said another office directly controlled over the trunk line for further extending the connection to said called line, and means including the switching apparatus at the remaining offices for clearing the trunk line of all connections while the 35 connection is being extended.

20. In a telephone system, an operator's switchboard, a plurality of automatic offices, a trunk line extending from the switchboard to all of said offices, a called line in one office, a called line in another office, other lines in the other offices, means at said one office for 45 establishing a connection between the calling line and the switchboard via the trunk line, means at said another office directly controlled from the switchboard over the trunk line for further extending the connection to the called line, means in said other offices for clearing the trunk line of all connections in such offices for a predetermined time during the further extension of the 50 connection, and means at each of said offices 55 for marking the trunk line busy at the respective offices as long as the connection is maintained.

21. In a telephone system, three offices connected by a trunk, switching devices in the 60 first and second offices connected to the trunk, other switching devices in the first and second offices, means at the third office for transmitting a series of impulses designating either the first or second office over 65 the trunk to set both of the connected switch-

ing devices, means controlled by the device in the office designated for connecting the other switching device in that office to the trunk, and means controlled by the device at the non-designated office for disconnecting 70 itself from the trunk.

22. In a telephone system, the combination comprising a trunk, switching devices connected to the trunk, automatic switches, means associated with each device for connecting an automatic switch to the trunk, time delay means associated with each device for disconnecting the device from the trunk, means for simultaneously operating said devices, and circuit connections for operating either said connecting means or said delay means under control of the associated devices. 75

23. In a telephone system, a two-conductor trunk, a plurality of relays normally connected to the two trunk conductors, a plurality of other relays, a switching device associated with each of said first relays, means for operating said first relays over the two trunk conductors in parallel to set their 80 associated devices, and means responsive to the setting of the devices for disconnecting said first relays from the trunk conductors and for connecting said other relays thereto. 85

24. In a telephone system, a trunk a plurality of switching devices connected to the trunk, a non-numerical switch associated with each of said devices, other trunks accessible to said switches, means for simultaneously setting said devices to corresponding positions, means responsive to the setting of the devices for disconnecting the same from the trunk line and for connecting the switch associated with a particular one of said devices to the trunk line, and means in the switch operated responsive to its connection with the trunk for effecting a connection between the trunk and one of said other trunks. 90

In witness whereof, I hereunto subscribe my name this 20th day of August, A. D. 110 1931.

NORMAN H. SAUNDERS.

In witness whereof, I hereunto subscribe my name this 20th day of August, A. D. 115 1931.

CLARENCE E. LOMAX.
